UNITED STATES PATENT OFFICE.

FLOYD K. RICKS, OF CANTON, ILLINOIS.

WAGON RUNNING-GEAR.

1,165,287.

Specification of Letters Patent. Patented Dec. 21, 1915.

Application filed September 7, 1915. Serial No. 49,322.

To all whom it may concern:

Be it known that I, FLOYD K. RICKS, a citizen of the United States, residing at Canton, in the county of Fulton and State of Illinois, have invented a new and useful Wagon Running-Gear, of which the following is a specification.

The present invention appertains to vehicle running gears, and is particularly an improvement over my Patent No. 610,921, issued September 20, 1898.

It is the object of the invention to provide a novel and improved running gear embodying means connecting the front and rear axles whereby they are swung in opposite directions when the front axle is turned, so that the wagon or vehicle can turn a short corner, the present device embodying improved details of construction to enhance the utility and efficiency of the structure.

The present device is also simple, light and inexpensive in construction.

With the foregoing and other objects in view which will appear as the description proceeds, the invention resides in the combination and arrangement of parts and in the details of construction hereinafter described and claimed, it being understood that changes in the precise embodiment of the invention herein disclosed can be made within the scope of what is claimed without departing from the spirit of the invention.

The invention is illustrated in the accompanying drawings, wherein:

Figure 1 is a plan view of the improved running gear with the wheels removed. Fig. 2 is an enlarged perspective view of one of the front skeins or spindles. Fig. 3 is an enlarged sectional detail of one of the rear skeins or spindles, this section being taken on the line 3—3 of Fig. 1. Fig. 4 is an enlarged perspective view of one pair of tie rods and their sleeve. Fig. 5 is an enlarged sectional detail taken on the line 5—5 of Fig. 1.

In carrying out the invention, there are provided front and rear pairs of skeins or spindles 1 and 2, respectively, which are hollow or socketed which are tapered exteriorly and interiorly. These skeins or spindles are constructed of suitable metal and are slipped or fitted upon the tapered ends 3 of the front and rear axles 4 and 5, respectively, said axles being constructed of wood or other suitable material. The skeins

provide convenient means for applying the wheels (not shown) to the ends of the axles, the wheels being journaled upon the skeins in the usual manner. The free ends of the skeins have reduced threaded portions 6 for the reception of nuts for holding the hubs of the wheels upon the skeins, and the skeins are provided between their ends and near their inner ends with collars 7, against which the inner ends of the hubs are adapted to rest.

The front skeins 1 are provided at their inner ends with forwardly projecting ears 8 which are apertured for the reception of the hooks 9 of V-shaped rods 10 which are terminally attached to opposite sides of the wagon tongue 11, the hooks 9 being provided at the crotch portions of the rods 10. The tongue 11 is thus attached to the front skeins 1, and this provides effective means for fastening the tongue to the front axle. The skeins 1 and 2 are provided at their inner ends with vertical hinge butts or extensions 12 having vertical bores 13 extending therethrough. The butts 12 of the skeins 1 project rearwardly, while the butts of the rear skeins project forwardly. Pins 14 project through the bores 13 and have their ends projecting.

Crossed reach bars 15 and 16 are connected to the pins 14, said reach bars being disposed diagonally or obliquely of the running gear, as clearly seen by reference to Fig. 1. Slidable upon each of the reach bars is a pair of sleeves 17 of rectangular cross section, similar to the cross section of the reach bars, and the sleeves of the reach bars are mounted adjustably thereon near the terminals thereof. The sleeves 17 are held in adjusted positions by means of vertical pins 18 engaged downwardly through suitable apertures provided in the sleeves 17 and through apertures 19 with which the bars 15 and 16 are provided. The apertures 19 are arranged in series, whereby the sleeves 17 may be adjusted for shortening or lengthening the distance between the axles, which ever is preferred. The sleeves 17 have upper and lower lugs 20 at their remote ends through which threaded bores 21 extend parallel with the reach bars. A pair of tie rods 22 is assembled with each sleeve 17, certain ends of the rods 22 being threaded through the bores 21 and the other ends of the rods 22 being provided with eyes 23 embracing or pivotally engaging the pin 14 of the re-

spective skein. The rods 22 are disposed above and below the respective bars parallel therewith, and serve to connect the reach bars with the skeins, whereby the reach bars 5 can swing relative to the axles, when the axles are swung. The remote terminals of the upper rods 22 of the lower reach bar 16 are offset upwardly, as at 24, to space the bar 16 below the bar 15, and the remote terminals of the lower rods 22 of the reach bar 15 are offset downwardly to raise the bar 15 above the bar 16. The rods 22 of the reach bar 15 are just the reverse of the rods 22 of the reach bar 16 illustrated in Fig. 4, 10 as will be readily understood. The reach bars 15 are thus spaced vertically and are separated so that they will not rub against one another.

The various parts of the running gear 20 may be readily assembled and adjusted, and the running gear is not only efficient and practical in construction, but is also light in weight, and is comparatively simple and inexpensive to manufacture.

25 With the present running gear, the same

as with other running gears of this character, when the front axle is swung in one direction, the rear axle is swung in the other direction, whereby a short turn may be made.

Having thus described the invention, what is claimed as new is:

1. A running gear embodying axles, crossed reach bars, adjustable sleeves upon the reach bars, and pairs of rods threadedly engaging said sleeves and pivotally connected to said axles. 35

2. A running gear embodying axles, pins attached thereto, crossed reach bars, adjustable sleeves upon the reach bars and having upper and lower lugs, and pairs of upper and 40 lower rods threaded through said lugs and having eyes embracing said pins.

In testimony that I claim the foregoing as my own, I have hereto affixed my signature in the presence of two witnesses.

FLOYD K. RICKS.
